UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

HOIST.

Application filed May 16, 1925. Serial No. 30,756.

To all whom it may concern:

Be it known that I, CHARLES C. HANSEN, a citizen of the United States, and a resident of Easton, county of Northampton, State of Pennsylvania, have invented a certain Hoist, of which the following is a specification, accompanied by drawings.

This invention relates to hoists and more particularly to hoists of the double drum type in which there is provided a main driving element which is adapted to actuate one or the other of two drums depending upon the direction of the rotation.

One object of the invention is to construct a hoist of this character of relatively few parts and having a positive drive. Another object is to arrange the drum driving elements so as to simplify and strengthen the hoist structure. Other objects of the invention are to brace the supporting standards by means of a center stationary or revolving shaft, and to drive the drums by a gear carrying a swinging pawl adapted to engage alternatively one drum or the other depending upon the direction of rotation of the motor. Still another object of the invention is to provide adequate support for the pawl to eliminate twisting and breaking strains in the pawl itself.

The invention will be more clearly understood by reference to the following description and the accompanying drawings in which,

Figure 1 is a side elevation of a hoist constructed in accordance with the practice of the invention, parts being broken away to show more clearly the internal construction;

Figure 2 is a perspective view showing the pawl removed from the main driver and portions of the ratchet rings with which the pawl cooperates to rotate the drums;

Figure 3 is a front elevation partly in longitudinal section of a modification of the invention in which the drums are adapted to rotate with respect to the supporting shaft; and

Figure 4 is a side elevation of the hoist, the parts being broken away to show the internal construction; and

Figure 5 is a perspective of the driving

gear and pawl showing more particularly the pawl mounting.

Referring to the drawings the hoist comprises a base A having standards B on either end adapted to support a shaft C provided with suitable journals D rotating in boxes of bearing metal and formed to resist end thrust of the shaft. Upon the shaft C are mounted two drums E and F each of which is provided with a bearing sleeve G rotatable on the shaft C.

The drum E is provided with a ratchet ring H having teeth preferably extending inwardly but lying in radial directions. The ring H may, if desired, be formed integrally with the drum and be disposed internally on the inner flange J at the side of the drum E. Similarly the drum F is provided with a flange K within which is disposed a ratchet ring L. The teeth of the ratchet rings H and L extend in opposite directions since the drums E and F are to be rotated oppositely.

The drums E and F are adapted to be driven by a main driving element which may be a gear O keyed to the shaft C. A boss P on the driver O is provided with a bore Q within which a pawl R is rotatably mounted. The pawl R is formed in two parts S and T entirely alike, each having a cylindrical bearing portion U with a dog tooth V extending at an angle therefrom. The ends of the bearing portions U are shaped to engage each other and prevent rotation therebetween and to this end shoulders W are provided at the ends of the bearing portions U. The two parts S and T are held together by a bolt X passing through the center of the pawl.

The dog teeth V are adapted to engage one or the other of the ratchet rings H and L depending upon the direction of rotation of the driver O. These dog teeth lie very close to the teeth of the ratchet rings so that one or the other of the teeth V is in engagement with one of the ratchet rings. Thus, when the driver O rotates in one direction the teeth on the ratchet ring L will kick the adjacent dog tooth V inwardly and cause the opposite tooth V to move outwardly to engage the

teeth on the ratchet ring H. Upon rotation of the driver O in the opposite direction, the teeth on the ratchet rings H rock the pawl so that the other dog tooth V engages the tooth on the ratchet ring L.

For rotating the driver O any suitable means may be employed as for instance a worm Y journalled in a suitable gear case Z which is adapted to fit closely against the flanges J and K of the drums E and F to prevent dust and dirt from entering.

From the manner of driving the drums E and F it will be seen that one of the drums is loose while the other is being driven. Therefore, if desired a brake may be provided to prevent overrunning of one drum, as for instance F, by means of a friction plunger b mounted in a plug e in the standard B and pressed into engagement with the outer flange d of the drum F by means of a coil spring e held in place within the plug c by a cap f. If desired a similar drag may be provided on the flange g of the drum E.

In the embodiment shown in Figure 3, the drums h and j are rotatably mounted on the shaft k and a drive gear such as the worm wheel o is provided with anti-friction bearings p held in place on the shaft k by the nuts q. The shaft k is stationary and forms with the base z and bearing standards B a rigid brace for the hoist. The shaft k is provided with shoulders r against which suitable washers s are adapted to bear. The washers s provide end bearings for the drums h and j. Renewable bushings t flanged at their ends to bear against the bearings D are provided with bearings for the drums h and j on the shaft k.

The pawl R is preferably mounted in a bushing u set into the bore Q in the boss P. Means are provided for supporting the pawl R along the entire length of the bearing portions U and especially at the heel or portion behind the teeth V. To this end the bushing u is arranged to extend outwardly to the edges of the two parts S and T at the rearward side of the pawl, and is cut away as shown at v to accommodate the teeth V and to permit slight rotation of the pawl. The remaining portion w of the bushing u receives the thrust of the pawl thereby preventing bending strains in the bolt X.

The main driving element or gear O may be driven in any suitable manner. A preferred arrangement is shown in Figure 4 in which the worm Y is mounted on the drive shaft of a motor (not shown) within a casing x suitably supported on the gear case Z and controlled by means of a lever y associated with the throttle valve of the motor.

Preferably the motor within the casing x is arranged with its axis transverse to the

shaft C and in order to balance the drums E and F and the motor within the casing x, the standards B are arranged to support the shaft C off center on the base z. The base z is adapted to be clamped to a plate 70 2 or to a cylindrical column, a circular jaw 3 being provided for this purpose.

In operation when the motor within the casing x is rotated in one direction causing the worm wheel O to rotate in a clockwise 75 direction (Figure 4), the teeth on the ratchet ring H trip the corresponding tooth V rocking the pawl R and causing the opposite tooth V to engage the ratchet ring L. Upon reversal of direction of rotation of the 80 motor within the casing x the worm wheel O rotates in the opposite direction causing the teeth on the ratchet ring L to rock the pawl R to engage the teeth on the ratchet ring H. The thrust of the teeth V is taken by that portion of the bushing u which extends at w and prevents twisting in the pawl R.

In practice, a hoist of this type is used mainly for pulling a load in one direction 85 and returning the receptacle, such as the scraper or mine slusher, empty in the opposite direction, therefore, the load comes mainly on one of the drums. The wear is therefore unequal on the dogs V and one of them may need replacement while the other is in good condition. By this method of constructing the pawl R, the worn half of the pawl may be replaced without the necessity of replacing the entire pawl and the construction is substantially as solid and rigid as though the pawl were made in a single piece.

I claim:

1. A hoist comprising a pair of drums each provided with a ratchet ring having teeth extending in opposite directions, a driver between the drums, a pawl mounted on said driver having teeth for selectively engaging with the ratchet rings, said pawl comprising a central bearing portion and oppositely extending teeth adjacent the ratchet rings, and means to receive the thrust at the heel of the pawl teeth. 105

2. A hoist comprising a pair of drums each provided with a ratchet ring having teeth extending in opposite directions, a driver between the drums, a pawl mounted on said driver having teeth for selectively engaging with the ratchet rings, said pawl comprising a central bearing portion and oppositely extending teeth adjacent the ratchet rings, and means to receive the thrust at the heel of the pawl teeth including a bushing 110 forming a bearing extending to the outer edges of the pawl and mounted in the driver. 115

3. A hoist comprising a pair of drums each provided with a ratchet ring having teeth extending in opposite directions, a driver, and a pawl mounted on said driver 120

125

130

for engaging selectively with the ratchet rings and formed in two complementary parts, each having a dog tooth and a cylindrical bearing portion.

5 4. A hoist comprising a pair of drums each provided with a ratchet ring having teeth extending in opposite directions, a driver, and a pawl mounted on said driver for engaging selectively with the ratchet 10 rings and formed in two similar complementary parts, each having a dog tooth and a cylindrical bearing portion.

5 5. A hoist comprising a pair of drums each provided with a ratchet ring having teeth extending in opposite directions, a driver, and a pawl mounted on said driver for engaging selectively with the ratchet 15 rings and formed in two similar complementary parts and ends to engage each other 20 adapted to be bolted together.

6. A hoist comprising a pair of drums each provided with a ratchet ring having teeth extending in opposite directions, a main driver between the rings and a pawl on 25 said main driver adapted to engage the rings selectively, said pawl being formed in two complementary parts each having a cylindrical bearing portion and a dog tooth extending at an angle therefrom, said parts having 30 ends adapted to engage each other and arranged to be bolted together.

7. A hoist comprising a pair of drums each provided with a ratchet ring having teeth extending in opposite directions, a 35 main driver between the rings and a pawl on said main driver adapted to engage the rings selectively, said pawl being formed in two similar interchangeable complementary parts

each having a cylindrical bearing portion and a dog tooth extending at an angle therefrom, said parts having ends adapted to engage each other and arranged to be bolted together. 40

8. A hoist comprising a pair of drums each provided with a ratchet ring having teeth extending in opposite directions, a main driving gear between the ratchet rings, and a pawl carried by the driving gear and adapted to rock into engagement selectively 45 with one or the other of the rings depending 50 upon the direction of rotation of the gear, said pawl being formed in two similar complementary parts adapted to engage each other at their ends each provided with a cylindrical bearing portion and dog tooth extending at an angle therefrom to engage the teeth of said rings and a bolt extending through the pawl and arranged to secure the two parts to each other.

9. A hoist comprising a central shaft, a 60 pair of drums rotatable on the shaft, each drum being provided with a ring having radial teeth extending in opposite directions, a main driving gear on the shaft between the drums and a pawl carried by the main driving gear adapted to engage said rings selectively, said pawl including two symmetrical parts with oppositely extending dog teeth, each part having a bearing portion with co-operating notch ends and at an angle with 65 70 said dog teeth and a bolt extending through the pawl to secure the two parts together.

In testimony whereof I have signed this specification.

CHARLES C. HANSEN.
